UNITED STATES PATENT OFFICE.

THRASYBULE D. LAZARIDES, OF NEW YORK, N. Y.

TURBINE.

1,161,140.

Specification of Letters Patent. Patented Nov. 23, 1915.

Application filed July 20, 1914. Serial No. 851,861.

To all whom it may concern:

Be it known that I, THRASYBULE D. LAZARIDES, of New York, in the county of New York, and in the State of New York, have invented a certain new and useful Improvement in Turbines, and do hereby declare that the following is a full, clear, and exact description thereof.

My invention relates to turbines, and has for its object to provide a reversible, combined reaction and impulse turbine, adapted to utilize a gas or fluid, particularly steam, in an economical and efficient manner, and for the production of results hitherto unattained in apparatus of this type.

For purposes of illustration, one embodiment of my invention has been shown in the accompanying drawings, in which—

Figure 1 is a longitudinal section; Fig. 2 a section taken on line 2—2 of Fig. 1, looking in the direction of the arrows; Fig. 3 a perspective of a short section of impulse buckets; Fig. 4 a bottom view of a pair of steam passages; Fig. 5 an elevation of a pair of steam passages; Fig. 6 a section taken on line 6—6 of Fig. 1, looking in the direction of the arrows; Fig. 7 a section taken on line 7—7 of Fig. 6, looking in the direction of the arrows; Fig. 8 an enlarged, sectional detail view of the ball-bearing mounting for the rotors; Fig. 9 a front elevation of an operating valve; Fig. 10 a vertical section of the operating valve; and Fig. 11 a horizontal section of the operating valve taken on line 11—11 of Fig. 10, looking in the direction of the arrows.

Similar reference characters refer to similar parts throughout the drawings.

A main shaft is indicated at 1, supported in any desired manner as by standards 2. Secured to said main shaft 1 is a rotor 3, of which there may be as many as desired, the embodiment illustrated showing two such rotors.

Each rotor 3 is provided with any desired number of reaction conduits 4 and 5. Reaction conduits 4 are adapted to receive steam (if that be the motive power used) to impart rotation to the rotor in one direction, as clockwise (Fig. 2); and conduits 5 are adapted to receive steam to impart rotation to the rotor in reverse direction,

as contra-clockwise (Fig. 2). In the embodiment illustrated in the drawings (Fig. 2), the size of each reaction conduit decreases from its entrance to its exit, but the variance may be modified, as well as the angle of curvature, to accord with the results desired to be obtained from each particular design of apparatus. Each rotor also is provided with any desired number of impulse buckets 6 and 7. Impulse buckets 6 are adapted to receive steam to impart rotation to the rotor in one direction, as clockwise (Fig. 2); and impulse buckets 7 are adapted to impart rotation to the rotor in reverse direction, as contra-clockwise (Fig. 2).

Secured to the casing 8 of the turbine or integral therewith are steam passages 9 and 10. Passages 9 are adapted to conduct steam from reaction conduits 4 to impulse buckets 6, and passages 10 are adapted to conduct steam from reaction conduits 5 to impulse buckets 7. The outer walls of said passages are formed to provide a space therebetween as indicated at 10' (Fig. 2) in order to permit the escape of steam from casing 8 to the exhaust.

If it be desired to turn main shaft 1 in a clockwise direction (Fig. 2), steam is admitted through pipes 11 (at the left of Fig. 1), to channels 12 (Figs. 1 and 2). From channels 12 the steam will pass into reaction conduits 4 in each rotor, and from thence through passages 9, which cause the steam to impinge on impulse buckets 6. The steam impinging on brackets 6 (or 7) escapes through openings 13 in the casing to exhaust pipe 14 (Fig. 2). Spaces 10' are provided (Fig. 2), which permit the steam to pass freely between the space between the rotors and the space at each side of the rotors, so that the steam can escape through all the openings 13. It will be evident that the passage of the steam through the turbine is utilized thrice to impart rotation to the rotor: first, its passage through reaction conduits 4; second, its impingement on passages 9 which tends to increase the force of the steam on reaction conduits 4; and third, its impingement on impulse buckets 6.

If it is desired to rotate the main shaft in

2

a contra-clockwise direction (Fig 2), steam is admitted through pipes 15 to channels 12' from whence it will pass into reaction conduits 5, through passages 10, and be impinged on impulse buckets 7. The direction of rotation thus can be stopped and reversed almost instantly by shutting off the steam from one set of entrance pipes as 11, and admitting it at the other set of entrance pipes as 15, and vice versa. It is preferable, but not essential, that a plurality of converging entrance pipes 11 and of converging entrance pipes 15 be provided so that the streams of incoming steam meet at an angle and thus are transmitted with increased force in the desired direction into their respective channels. The channels are so curved as to convey the steam to the reaction conduits without abrupt change of direction. To aid in stopping the apparatus quickly and with a minimum of vibration, exhaust pipe 14 (Fig. 2) is provided with a closure valve 16 of any desired type and controlled in any desired manner, as by a rod 17 connected to a handle 18 (Fig. 9). If main shaft 1, for example, be rotated in a clockwise direction (Fig. 2) by the entrance of steam through pipes 11, and it be desired to stop or reverse its rotation, steam is shut off from pipes 11, introduced through pipes 15, and closure valve 16 shut to any desired degree, thereby utilizing the increased pressure of the steam in reaction conduits 5, on passages 10, on impulse buckets 7, and on all portions of the rotating parts exposed to the pressure of the steam, to stop rotation. In order to prevent damage from a too great pressure of steam under these conditions, a by-pass 19 (Fig. 2) is provided in exhaust pipe 14, entrance to which is closed by a spring-pressed valve 20, which is so adjusted as to open when the steam pressure reaches a predetermined amount.

45 The right and left thrust of the rotors (Figs. 1 and 8) is taken up by a ball-bearing (Fig. 8) consisting of bearing-plate 21 secured to the rotor, bearing-plate 22 secured to casing 8, and balls 23 therebetween.

50 To prevent the escape of steam through the ball-bearing, a packing is provided consisting of packing material 24, held in position by a washer 25, spring 26, and nut 27. In order to protect the ball-bearing, as, for example, from any vibration which might result from quick stopping or reversing, bearing-plate 22 is secured to casing 8 by some device having a suitable degree of flexibility, the embodiment illustrated in

55 the drawing showing a support 28 of suitable leather or its functional equivalent, said washer preferably being slack and not drawn tight in order to permit transverse movement of the rotor with respect to the casing. In order to hold the leather (if

that be used) in place without tearing, a wire mesh 30 is placed over leather 28, and the whole held in place by bolts 29 and washers 31 and 31'. This construction permits an almost instantaneous stopping and reversal of the rotors, which has not been possible heretofore owing to the vibration transmitted by the rotors and shaft to the casing. The vibration not only injures the entire turbine, but causes the casing to leak, particularly at points where packing is employed. The flexible construction minimizes and prevents the transmission of this vibration to the casing, and as it is not affected by rotor and shaft vibration, always maintains the casing steam-tight.

As an aid to quick starting of the turbine, and to supply additional motive power, auxiliary pipes 32 and 33 are provided (Fig. 1), by means of which the steam may be impinged directly upon the buckets. Auxiliary pipes 32 are adapted to turn the rotor in a clockwise direction (Fig. 2), and auxiliary pipes 33 are adapted to turn the rotor in a contra-clockwise direction (Fig. 2).

In order to start, stop, control, and otherwise manipulate the apparatus above described, some efficient means of control is necessary, one embodiment of which I have illustrated in Figs. 9, 10, and 11 of the drawings. The operating valve there disclosed consists of a casing 40 to which steam is admitted through an opening 41. To illustrate the principle of operation, two sets of egress pipes are shown (Fig. 10), one set consisting of pipes 42 and 43 conducting steam to operate main shaft 1 in a clockwise direction (Fig. 2), and the other set of pipes 44 and 45 conducting the steam to operate the main shaft in a contra-clockwise direction (Fig. 2). Pipe 42 is connected in any desired manner with pipes 11 (Fig. 1), and pipe 43 with auxiliary pipes 32. In like manner pipe 44 is connected in any desired manner with pipes 15, and pipe 45 with auxiliary pipes 33. Inside the valve casing are two slidable valve members 46 and 47, each consisting of two semi-circular pieces held in place by split spring members 49'. Outer valve member 46 has an opening 47 normally in line with pipes 42 and 43, and an opening 48 normally in line with pipes 44 and 45. Inner valve member 49 has an opening 50 adapted to be moved into line with opening 47 of the outer valve member 46, and an opening 51 adapted to be moved into line with the other opening 48 of the outer valve member 46.

The movement of inner valve member 49 is controlled by a shaft 52 adapted to be raised and lowered in any desired manner, as by a wheel 54, shaft 55, bevel gears 56, and nut 53 rotatably mounted in the frame

and having screw threads engaging screw threads on said shaft 52. The position of shaft 52 and therefore of inner valve member 49 is indicated by any desired means as by an arm 57 secured to shaft 52 and having a pointer 58 adjacent a suitably graduated scale 60.

The outer valve member 46 is operated by a shaft 61 adapted to be controlled by a 10 governor secured to main shaft 1 (Fig. 1) and also by a handle 75 (Fig. 9). Any desired form of governor may be used, but I have illustrated in Fig. 1 a very sensitive and satisfactory form of governor mounted 15 on main shaft 1, and consisting of weights 62 slidably mounted on a rod 63 secured to main driving shaft 1, said rod being provided with heads 63' to prevent weights 62 flying off and causing injury, in case of accident to the governor. Weights 62 are connected by arms 66 to a sleeve 64 having a flange 65, said sleeve being slidably mounted on main shaft 1, and maintained normally in outward position by a spring 67, 20 the pressure of which may be regulated by a threaded nut 67'. As the speed of main shaft 1 increases, weights 62 tend to move outwardly, thereby moving sleeve 64 to the right against the pressure of spring 67. 25 This movement is imparted to shaft 61 of outer valve member 46 by a rod 68 having a roller 69 adapted to bear on flange 65 of said sleeve 64, the other end of said rod being connected in any suitable manner to 30 said shaft 61 of outer valve member 46. In the embodiment illustrated (Fig. 9), the end of rod 68 adjacent the valve ends in a sleeve 79 slidably mounted on a rod 68' having a threaded nut against which bears said sleeve 35 79. Said rod 68' is connected to a toggle joint 40 consisting of toggle arms 70, 76. Toggle arm 70 is connected to a sleeve 71 slidably mounted on shaft 61, the position of said sleeve being controlled through levers 72, 45 73, and 74, and by handle 75. The other toggle arm 76 is connected to a collar 76' which is secured to shaft 61. A spring 77 mounted on shaft 61 between the valve casting and fixed collar 76' tends normally to 50 hold said outer valve member 46 in normal position with its openings 47 and 48 in line with the egress pipes. The position of outer valve member 46 is indicated by an arm 80 secured to fixed sleeve 76' and having a 55 pointer 81 adjacent a graduated scale 82.

The operation of the apparatus is as follows: When the operating valve is in the position shown in Figs. 9 and 10, steam will be admitted thereto through opening 41, but 60 cannot reach the turbine from the valve owing to the position of inner valve member 49. If it is desired to rotate the main shaft in a clockwise direction, which we will assume is forward in accordance with the 65 graduated scale shown on Fig. 9, said inner

valve member 49 is raised by means of wheel 54 until its opening 50 is in line with opening 47 of outer valve member 46 and thus with pipes 42 and 43. The steam will pass through opening 50 of inner valve member 49, through opening 47 of outer valve member 46, through pipe 42 into pipes 11 (Fig. 1), and also through pipe 43 into auxiliary pipes 32 (Fig. 1). This will start the turbine in the desired direction as described above. As the speed of main shaft 1 increases, weights 62 of the governor will move outward, thereby, in the manner described above, raising outer valve member 46 by rods 68, 68', toggle arm 76, and shaft 61. As the speed increases, outer valve member 46 will be raised until steam is cut off from pipe 43, thereby shutting off the steam from auxiliary pipes 32, and operating the turbine through pipes 11. As the speed increases still more, outer valve member 46 will continue to rise, gradually cutting off steam from pipe 42. If a greater speed of rotation is desired, handle 75 (Fig. 9) is moved to the right, thereby lowering sleeve 71 of the toggle joint, which causes outer valve member 46 to be lowered, admitting more steam, first to pipe 42 and then to pipe 43. A constant speed of rotation therefore is obtained by the governor, which may be varied by operating handle 75. The operation of the governor may be adjusted by nut 67' on main shaft 1 (Fig. 1) and by nut 78 on rod 68' (Fig. 9). The operation is the same if it is desired to rotate main shaft 1 contra-clockwise or in a reverse direction, with the exception that wheel 54 will be turned in the opposite direction, thereby lowering inner valve member 49 and bringing its opening 51 in line with opening 48 of outer valve member 46 and thus in line with pipes 44 and 45. As the speed increases, outer valve member 46 will rise in the same manner already described to cut off steam from pipe 45 connected with auxiliary pipes 33, and next from pipe 44 connected with pipes 15, and is adapted to be controlled in the same manner by handle 75. If it is desired to stop and change the direction of rotation very quickly, handle 18 is operated to shut closure valve 16 (Fig. 2) to any desired extent, thereby utilizing the increased steam pressure to stop the turbine almost instantly in the manner described above. When the turbine is stopped and begins to reverse, closure valve 16 is opened in order to allow free exhaust for the steam as in ordinary operation.

It is obvious that my invention is capable of many modifications and that its proportions may be altered or other embodiments thereof constructed without departing therefrom or from the scope of the claims. The use of terms is intended to be illustrative merely, and not restrictive.

Having thus described one embodiment of my invention, what I claim is:

1. In a turbine, a rotor provided with impulse buckets, steam passages to convey steam to said impulse buckets, and auxiliary steam-conveying means independent of and extending into said passages and adapted to impinge steam directly on said impulse buckets. 55
2. In a turbine, a casing, a rotor, means on said casing and on said rotor adapted to utilize the action of steam thrice for imparting rotation to said rotor, means to convey steam to said rotor, and auxiliary steam-conveying means independent of said second-named means to convey steam to said rotor at a separate point of entrance. 60
3. In a turbine, a rotor provided with impulse buckets, steam passages to convey live steam to said impulse buckets, and auxiliary steam-conveying means independent of and extending into said passages and adapted to impinge live steam directly on said impulse buckets. 65
4. In a turbine, a casing, a shaft, a rotor mounted on said shaft having reaction conduits and impulse buckets adapted to receive steam to impart rotation to said rotor, steam passages on said casing adapted to convey steam from said reaction conduits to said impulse buckets, and auxiliary steam-conveying means in said steam passages. 70
5. In a turbine, a casing, a shaft, a rotor mounted on said shaft having reaction conduits and impulse buckets adapted to receive steam to impart rotation to said rotor, steam passages on said casing adapted to convey live steam from said reaction conduits to said impulse buckets, and auxiliary steam-conveying means in said steam passages. 75
6. In a turbine, a rotor, and means to admit steam to said rotor comprising a plurality of steam inlets having converging axes whereby the streams of incoming steam meet at an angle and are transmitted with increased force in a horizontal direction. 80
7. In a turbine, a rotor, and means to admit steam to said rotor comprising a plurality of steam inlets having converging axes and adjacent outlets whereby the incoming steam from each outlet meets the incoming steam from an adjacent outlet, and the streams are transmitted with increased force in a horizontal direction. 85
8. In a turbine, a rotor having reaction conduits and channels curving into said conduits to convey steam thereto, and converging steam inlets whereby the steam is transmitted with increased force into said channels. 90
9. In a turbine, a rotor having reaction conduits and impulse buckets, and a casing provided with steam passages adapted to convey steam from said reaction conduits to said impulse buckets and also with means to permit steam to pass from one side of said rotor to the other. 95
10. In a turbine, a rotor having reaction conduits and impulse buckets, a casing provided with steam passages adapted to convey steam from said reaction conduits to said impulse buckets and also with passages between the walls of said steam passages to permit the escape of steam from said casing into the exhaust. 100
11. In a turbine, a casing provided with a plurality of exhaust openings, a rotor having reaction conduits and impulse buckets adapted to receive steam to impart rotation to said rotor, and steam passages on said casing adapted to convey steam from said reaction conduits to said impulse buckets and provided with spaces between said steam passages whereby the exhaust steam may pass from one side of said rotor to the other and thence to all of said exhaust openings in said casing. 105
12. In a turbine, a casing, a rotor, means to admit steam to said casing to turn said rotor, means to permit the escape of steam from said casing after turning said rotor, and means to lessen the escape of steam from said casing in order to stop said rotor comprising a closure valve in the means to permit the escape of steam from said casing, and a by-pass around said closure valve provided with a spring-pressed valve. 110

In testimony that I claim the foregoing I have hereunto set my hand.

THRASYBULE D. LAZARIDES.
